UNITED STATES PATENT OFFICE.

HELEN T. HUEY, OF STONEHURST, PENNSYLVANIA.

WINDOW-CURTAIN GUARD.

Application filed March 31, 1926, Serial No. 98,775. Renewed November 2, 1928.

This invention relates to curtain holding devices, and more particularly to a device which is adapted to be secured to the inner side of a window casement adjacent the window jamb, and provided with a spring tensioned instantly adjustable arm for holding the lower portion of window curtains and the like, away from the window jamb, and to one side of the window casement when so desired.

The principal object of the invention is to provide a small, compact, and simple device which may be readily attached one to each side of a window casement, for holding a pair of window curtains or window draperies away from the window jamb, to prevent the curtains from blowing about when the window is opened for ventilation, or when it is necessary to clean the window pane, thereby preventing the curtain or curtains from becoming soiled.

Another object of the invention is to provide a curtain holding device as specified, which will prevent the disarrangement of window curtains or draperies, eliminate the necessity of folding, tieing or pinning, the curtains in an out-of-the-way position, one that will not mar the appearance of a window either from the inside or outside, and a device which may be placed in an out-of-the-way inoperative position, when it is desired to suspend the curtains in front of a window in the usual manner.

A further object of the invention is to provide a device as specified, which is cheap to manufacture, readily attachable, instantly adjustable, requiring a minimum of space, pleasing in appearance, and one that will not mar or deface the finished surface of a window casement.

Other objects of the invention will appear in the following detail description, and in the accompanying drawing, wherein:

Figure 1 is a fragmentary view in perspective of a window and casement therefor, showing the device as applied and in operative position.

Figure 2 is a plan view of the device per se with the attaching base thereof in section and with the right-hand position of the arm indicated in dotted lines.

Figure 3 is an end view of Figure 2, in the direction indicated by the arrows.

Figure 4 is a side plan view of the attached base per se.

Figure 5 is a detail view of the pivot stud.

Referring more particularly to the drawing, the invention comprises a metal base 10 of cup formation, with an oblong annular base flange 11 formed about its open end 12, and extended at right angles thereto. The flange 11 is also provided with a plurality of apertures 13 therein for securing the base 10 to a window casement. The top or closed end 14 of the base 10, is provided with a suitable opening 15 for partial projection there-through, of a shouldered pivot stud 16. This stud is further provided with an expansible spring 17, positioned about the shank 18 thereof, with one end of the spring resting on the shoulder formed by the head 19 and the other end of the spring adapted to engage against the underside 20 of the top 14. In order to retain the stud 16 in the base 10, against the tension of the spring 17, the protruding end of the stud 16 is provided with a transverse bore 21 which passes through the shank 18 for receiving the straight end portion 22 of a curved curtain engaging arm 23. The extreme end of the straight portion 22 of the arm is upset or flattened, as indicated at 24, for retaining and limiting the outward movement of the arm through the stud. The outer surface of the closed end 14 is also provided with a radially disposed, substantially semi-circular depression or recess 25 on each side of the opening 15 for receiving the straight portion 22 of the arm 23, in a normal laterally extended curtain engaging position.

In this connection, it is to be noted that the base 10 is secured to a window casement with the semi-circular recesses 25 positioned at right angles to a window jamb. The straight portion 22 of the arm 23, is rotatable while normally disposed in a laterally extended position in the recesses 25, eliminates the necessity of providing for a right and left-hand curtain holding device, by the simple expedient of turning the curved portion of the arm 23 to the right or left, as the case may be, with the curved portion of the arm 23, extended in a horizontal plane, as shown in Figure 2 of the drawing. The free end of the curved arm portion is finished into a ball point 26 for enhancing the appearance of the device, and eliminating possible injury to the curtains or the like, when retained by the arm 23.

From the foregoing description, taken in connection with the accompanying drawing, it will be readily apparent that I have pro-

vided a neat, simple, and highly efficient device for retaining and protecting the free ends of window curtains in an out-of-the-way position, when so desired, and while I have 5 shown and described one practical embodiment of my invention, it is to be noted that I do not limit myself to the exact construction as set forth, but deem myself at liberty 10 to make such changes and modifications as fairly fall within the scope of the appended 15 claims.

What I claim is:

1. In a window curtain guard, the combination with an inverted cup shaped base to 15 be attached to a window frame, of a headed stud having a shank mounted in the end of the base, said shank provided with an opening in one of its ends and a head at its other end, a curtain engaging and holding member 20 extending through said opening, spring means on the stud operable between said head and the end of the base, whereby sufficient tension is created to hold said member frictionally in engagement with the outer 25 side of said end of the base either in a horizontal or a vertical position.

2. In a window curtain guard, the combination with an inverted-cup shaped base to be attached to the side of a window frame, 30 of an added stud having a shank mounted in the end of the base, said shank having a shoulder at its inner end and provided with a transverse opening near its outer end, a curtain engaging and holding member with 35 one end portion straight extending through the transverse opening of the shank, the other end of said member being curved to engage with the curtain, one end of the base having transverse semi-cylindrical cavities in which 40 the straight portion of the member may engage to hold the member in a horizontal posi-

tion, a spring surrounding the shank of the stud and operable between said shoulder and the end of the base, whereby sufficient tension is created to hold said member frictionally 45 in engagement with the outer side of said end of the base in a vertical position, or in engagement with the cavities to hold the member in a horizontal position, said cavities being positioned diametrically opposite each other. 50

3. In a window curtain guard, the combination with an inverted cup-shaped base to be attached to the side of a window frame, of an added stud having a shank mounted in the 55 end of the base, said shank having a shoulder at its inner end and provided with a transverse opening near its outer end, a curtain engaging and holding member with one end portion straight extending through the transverse opening of the shank, the other end of 60 said member being curved to engage with the curtain, one end of the base having transverse semi-cylindrical cavities in which the straight portion of the member may engage to hold 65 the member in a horizontal position, a spring surrounding the shank of the stud and operable between said shoulder and the end of the base, whereby sufficient tension is created to hold said member frictionally in engagement with the outer side of said end of the 70 base in a vertical position, or in engagement with the cavities to hold the member in a horizontal position, said cavities being positioned diametrically opposite each other, a 75 protruding end of the member beyond the stud being offset or flattened at opposite points to limit the member in its longitudinal movement in one direction.

In testimony whereof I affix my signature.

HELEN T. HUEY.
